UNITED STATES PATENT OFFICE.

WILLIAM A. TURBAYNE, OF NIAGARA FALLS, NEW YORK, ASSIGNOR TO U. S. LIGHT & HEAT CORPORATION, OF NIAGARA FALLS, NEW YORK, A CORPORATION OF NEW YORK.

LAMP VOLTAGE-REGULATOR.

1,367,844.

Specification of Letters Patent.

Patented Feb. 8, 1921.

Application filed July 18, 1917. Serial No. 181,398.

To all whom it may concern:

Be it known that I, WILLIAM A. TURBAYNE, a citizen of the United States, residing at Niagara Falls, in the county of 5 Niagara and State of New York, have invented new and useful Improvements in Lamp Voltage-Regulators, of which the following is a specification.

The present invention relates to lamp 10 voltage regulators.

More particularly the invention relates to improved regulating means adapted to be inserted between the storage battery and translating devices in an electrical system 15 having a variable voltage source, as for instance, a car-lighting system. A great deal of difficulty has been experienced with lamp voltage regulators in use in car-lighting systems for the reason that they are called upon 20 to take care of wide variations in the supply voltage and wide variations in the lamp load. For instance, a heavy load may be used when the generator is inoperative. At this time the resistance of the lamp regulator should 25 be very small. At other times a low lamp load is used when the voltage across the terminals of the storage battery is high. At such times it is necessary that the lamp voltage regulator have a considerable re- 30 sistance.

An object of the present invention is to provide a lamp voltage regulator having a maximum range and involving only simple mechanism.

35 A further object is to provide a lamp voltage regulator which will provide close regulation over a wide range.

A further object is to provide a lamp voltage regulator of the compressible pile type 40 in which the paths of the electric currents may be changed to suit the necessities at the various stages over a wide range of regulation.

The one figure of the drawings represents 45 diagrammatically one embodiment of the present invention.

The numerals 1 and 2 represent conductors which may be connected to a variable voltage source, as for instance, a generator 50 driven from a car axle. Across the conductors 1 and 2 are connected a storage battery 3 and a lamp circuit 4, containing lamps 4^a. Connected in the lamp circuit 4 is a rheostat having a pair of compressible piles 5 and 6 55 and a solenoid 7. The pile 5 is divided into

two elements 8 and 9. The pile 6 is divided into two elements 10 and 11. The elements 9 and 10 are preferably composed of relatively thick disks whereby the total resistance of said elements 9 and 10 is relatively low under a given state of compression. The elements 8 and 11 are preferably composed of relatively thin disks whereby the resistance of said parts 8 and 11 is relatively high under the state of compression 60 above referred to. The piles 5 and 6 are preferably of similar construction and dimensions and have their longitudinal axes arranged in parallel. A yoke 12 is adapted to operate on adjacent ends of the piles 5 and 6. This yoke 12 is adapted to be operated by a lever 13 pivoted at the point 14. The lever 13 is adapted to be operated by a bell crank lever 15, pivoted at the point 16. The bell crank lever 15 is adapted to be operated by the solenoid 17 which is connected across the lamp circuit through adjustable resistance 18. Solenoid 7 is adapted to operate a bell crank lever 19 which controls a switch comprising contacts 20 and 21. Contact 20 is connected through a low resistance conductor to the mid-point between elements 8 and 9 of pile 5. Contact 21 is connected through a low resistance conductor with the mid-point between the elements 10 and 11 70 of the pile 6. Adjacent ends of the piles 5 and 6, distant from the yoke 12, are connected together and to the conductor 1. Adjacent ends of the piles 5 and 6 close to the yoke 12 are connected together and to one 75 terminal of the solenoid 7. The other terminal of the solenoid 7 is connected through the lamps to the conductor 2. A double pile rheostat has been illustrated, though the invention is not limited to that construction. 80

85 A mode of operation of the above described embodiment of the invention is substantially as follows: If only a comparatively low lamp load is being used, contacts 20 and 21 will be out of contact, and the 90 two piles 5 and 6 will be connected in parallel to be controlled by solenoid 17 through the yoke 12 to maintain substantially constant voltage across the lamps. The yoke 12, which should preferably have a pivotal connection with the lever 13, will rock to compensate for structural differences in the piles 5 and 6 which will be encountered in practice. In case a heavier load is used on the 95 lamp circuit 4, in which case it is desirable 100

105 110

to materially reduce the resistance of the rheostat, the solenoid 7 will be sufficiently energized to operate the bell crank lever 19 to close the contact 20 on contact 21, thereby connecting together the mid-points of piles 5 and 6. Circuit may now be traced from conductor 1 through low resistance element 10 to switch contact 21, switch contact 20, through the low resistance element 9, solenoid 7 and lamps 4^a, to the conductor 2. A certain amount of current will also flow through high resistance parts 7 and 8. The net result will be that the resistance of the regulator will be very materially reduced.

15 One embodiment of the present invention has been described in detail. Various modifications will occur to those skilled in the art. It is intended that this patent shall cover all such modifications as come within 20 the scope of the invention as defined by the appended claims.

What I claim as new and desire to secure by Letters Patent of the United States is:—

1. In combination, a compressible rheostat 25 having a plurality of compressible elements which under equal states of compression have different resistances, an element of higher resistance being in series with an element of lower resistance, voltage responsive means for operating said rheostat, and current responsive means for controlling a short circuit through said elements having the lower resistance.

2. In combination, in a circuit to be regulated, a compressible rheostat having a plurality of compressible elements which under equal states of compression have different resistances, and means for controlling said rheostat to put an element of higher resistance in series with an element of lower resistance or to form a short circuit around an element of high resistance through an element having the lower resistance.

3. In combination, in a circuit to be regulated, a rheostat including a pair of compressible piles, each composed of a plurality of compressible elements which under equal states of compression have different resistances, switching means for connecting said piles between said elements, voltage controlled means for operating said rheostat, and means controlled by the current in said circuit for operating said switching means.

4. In combination, in a circuit to be regu-

lated, a rheostat including a pair of compressible piles, both ends of one pile being electrically connected to the ends of the other pile, voltage controlled means for operating said piles, and current controlled means for connecting an intermediate point 60 of one of said piles to an intermediate point of the other of said piles.

5. In combination, in a circuit to be regulated, a compressible rheostat including a plurality of elements which under equal 65 states of compression have different resistances, switching means connected to said rheostat at points between said elements, and means responsive to the current in said circuit for closing said switching means. 70

6. In combination, in a circuit to be regulated, a rheostat including a pair of compressible piles, each pile being composed of a plurality of compressible elements which under equal states of compression have 75 different resistances, switching means connected to the ends of those elements having the lower resistance, and means responsive to the current in said circuit for operating said switching means. 80

7. In combination, in a circuit to be regulated, a rheostat including a plurality of compressible elements which under equal states of compression have different resistances, and means responsive to the current 85 in said circuit for selectively determining whether one low and one high resistance element shall be connected in parallel with another low and another high resistance element or each low resistance element shall be 90 connected in parallel with a high resistance element.

8. In combination, in a circuit to be regulated, a rheostat containing a plurality of compressible elements, certain of said elements having, under equal states of compression, a resistance different from that of certain other of said elements, means for selectively connecting said elements in parallel paths in one grouping and for connecting 100 said elements in the same number of parallel paths in another grouping, said selective means being responsive to the current flow in said circuit. 95

In witness whereof I have hereunto sub- 105 scribed my name.

WILLIAM A. TURBAYNE.
